METHOD OF AND APPARATUS FOR MAKING
COLOR CARDSSamuel H. Smith, Olmsted Township, Cuyahoga
County, Ohio

Application January 9, 1937, Serial No. 119,826

17 Claims. (Cl. 216—14)

This invention relates to a method of and to apparatus for making color cards of the kind having color chips mounted thereon and usually bearing indicia for identifying the color of each chip with a particular paint, pigment or the like. The invention relates particularly to separating color chips from strip stock and to affixing the chips to color card blanks. It is contemplated that suitable adhesive may be carried either on the color card blank or on the color strip for securing the chips to the blank; and also that feeding means of any approved type may be provided for advancing the stock as new chips are to be formed. The purposes of the invention are to improve the art of forming color chips from stock and affixing them to color card blanks; to provide for holding the chips substantially in pressure contact with a color card blank as they are separated from the stock; to provide efficient means for rendering the adhesive effective; to provide means which may be attached to apparatus of various kinds, as for instance, to well known types of printing presses, for adapting such apparatus to the production of color cards in accordance with this invention; and also to provide apparatus of the class described having an improved construction and relative arrangement of parts.

The features of the invention are illustrated in the accompanying drawings, wherein:

Fig. 1 is a side elevation of a machine for making color cards, showing the pressure transmitting members separated and illustrating the application of a solvent for the adhesive;

Fig. 2 is a view similar to Fig. 1, but showing the pressure transmitting members pressed together to form a color card;

Fig. 3 is a plan view of attachable means constituting one of the pressure transmitting members, showing this means in horizontal position for purposes of illustration;

Fig. 4 is a section on the line 4—4 of Fig. 3;

Fig. 5 is a section on the line 5—5 of Fig. 4;

Fig. 6 is a section on the line 6—6 of Fig. 4;

Fig. 7 is a detail view similar to Fig. 4, but showing both pressure transmitting members brought together to sever color chips from the stock and to affix the chips to a color card blank;

Fig. 8 is a face view of a color card;

Fig. 9 is an edge view of the card shown in Fig. 8;

Fig. 10 is an enlarged sectional view of a strip of stock from which the color chips are formed;

Fig. 11 is an end elevation taken from the right of the apparatus shown in Figs. 1 and 2,

with parts omitted and broken away, and illustrating the rack for supporting the strip stock;

Fig. 12 is a plan view of a cutter plate; and

Fig. 13 is a sectional view similar to Fig. 4, but showing only the cutter plates to illustrate the normal positions and the abutting relationship of the cutter plates.

The apparatus selected for illustration comprises a main frame 10 in which an oscillatory shaft 11 and a rotary shaft 12 are mounted. A crank arm 13 is fixed to the oscillatory shaft and carries a crank pin 14. A link 16 connects this crank pin to a similar pin 17 mounted on a wheel 18 which is fast on the rotary shaft. Power for operating the machine is transmitted to rotary shaft 12. One of the pressure transmitting members is in the form of a supporting plate or platen 19 which is fixed on the oscillatory shaft 11. Any suitable means (not shown) may be provided for releasably retaining a color card blank in position on this platen, as is well understood in the art. This platen carries a projection 21 which is engageable with a projection 22 of a self-closing valve 23 in a supply pipe 24 which leads to a spray nozzle 26 disposed above the platen as viewed in Fig. 1. The valve 23 and the pipe 24 may be supported by any suitable means, as by a bracket 27 mounted on the main frame.

The color chips 30 (Fig. 8) may be formed from narrow strips or ribbons of stock (Fig. 10) comprising paper or other suitable material 28, having on one side a layer or coating 29 of paint of the color and quality desired. Conveniently the other side of the stock may have a coating 31 of adhesive. This stock may be supplied from rolls 32 mounted on spindles or cores 33 which are rotatably supported in the rack 34 mounted on the main frame. The number of rolls of stock on each spindle and the number of spindles carrying such rolls may be determined from the number and arrangement of the color chips on the finished card. The illustrated apparatus is adapted to produce the card 35 shown in Figs. 8 and 9, and hence, there are five rolls of stock on each spindle to correspond with the five horizontal rows of color chips and four spindles to correspond with the four vertical rows of chips as viewed in Fig. 8. The rolls of stock are spaced along each spindle in vertical alignment with the rolls on the other spindles (Fig. 11).

An idler roll 36 is rotatably mounted at the top of the main frame and the strip stock is passed over this roller with the strips from the vertically aligned rolls in superposed relationship. Hence, from each group of vertically aligned

rolls there are four plies of stock, each from a different roll and therefore of a different color, which pass over the idler roller and downwardly between pairs of aligned feed rolls 37 and 38 (Fig. 4). These feed rolls are mounted on shafts 39 and 41 supported in bearing brackets 42 and 43. A spur gear 46 fixed on the shaft 39 meshes with a similar gear 46 which is fast on the shaft 41, thereby causing these shafts and the feed rolls to operate in unison.

The feed rolls may be caused to advance the stock intermittently by any suitable mechanism as, for example, by means of a ratchet wheel 47 fixed on shaft 41 (Figs. 1 and 2) and a spring 15 pressed feed pawl 48 carried by an oscillatory arm 49 having a longitudinal slot 51 in which a link 52 may be adjustably connected to vary the feeding stroke as is well understood. The other end of this link may be connected to the platen 19. A spring pressed pawl 53 may also be provided to prevent retrograde movement of the ratchet wheel while the feed pawl is being retracted preparatory to engaging a ratchet tooth for a feeding stroke.

25 A vertically disposed plate 56 (Fig. 1) is provided with guide channels 57 (Fig. 5) for receiving the stock from the feed rolls and conducting it to points along these channels at which the color chips are formed. Cutter plates 59, 61, 62 30 and 63 (Fig. 3) are disposed across this plate. Preferably each of these cutter plates is made of resilient material such as spring steel, and is provided with end portions 64 and 66 disposed in the same plane and adapted to be clamped 35 against the plate 56 as by means of angle strips 67 and 68 (Fig. 3) secured along the edges of plate 56 and overlying the end portions 64 and 66 of the respective cutter plates. Adjacent its end portions, each cutter plate is cut away to 40 form an intermediate portion 69 (Fig. 12) which is bent outwardly from the end portions so that these intermediate portions normally assume inclined positions substantially as shown in Figs. 4 and 13. Preferably the underside of the edge 45 71 of the intermediate portion is bevelled substantially as shown, and the edge 71 and the opposite edge 72 of the plate are squared so that the edge 71 of one plate may cooperate with the edge 72 of an adjacent plate to sever strip 50 stock disposed therebetween. The end portions 64 and 66 of cutter plates 59, 61 and 62 abut against the adjacent portions of the edges 72 of plates 61, 62 and 63, while the end portions of plate 63 abut against the squared edge of a 55 flat plate 73 affixed to the plate 56 and having a squared edge 72' which cooperates with the cutting edge 71 of cutter plate 63. Above the plate 56, retaining strips 74, 76, 77, 78, 79 and 60 81 may be arranged to overlie the edges of the guide channels to keep the stock therein. Adjacent each of the cutting edges 72 and 72' a yieldable support for the stock is provided by elastic rubber elements such as the tubes 82 which extend entirely across the plate 56 above the 65 guide channels and have their ends secured as by means of cement 83, 84 (Fig. 6) to the angle strips 67 and 68 carried by plate 56.

70 Preferably the plate 56 and parts associated therewith are formed as a unit for attachment to existing machines, such as printing presses or other apparatus having pressure transmitting members or surfaces movable relatively toward and from each other. Thus the idler roll 36 preferably is carried by arms 86, 87 formed as 75 a part of the bearing brackets 42 and 43 (Figs. 3,

4 and 5) which are attached to plate 56 by bolts 88. The plate 56 may be mounted on the main frame in any approved manner (not shown).

In the operation of this apparatus the strips of color stock are taken from the underside of the supply rolls so that the tendency of the advancing ends of the strips will be to curl outwardly over the rubber tubes 82 when given an opportunity to do so. In arranging the stock for the first operation, the undermost ply in each 10 guide channel is advanced so that its leading edge projects sufficiently across the cutting edge 72' of plate 73 to form a chip of the desired size. Similarly the adjacent ply is brought across the edge 72 of plate 63, the next ply is brought across the edge 72 of plate 62, and the outer ply is advanced across the edge 72 of plate 61. The color stock is also arranged so that its adhesive bearing sides are disposed outwardly from the guide channels. A color card blank is positioned on the platen 19 and the solvent for the adhesive of the color strips may be applied over the blank as a fine mist delivered from the spray nozzle 26. It will be understood that only enough of the solvent is applied to render the adhesive fully 20 effective.

The apparatus may then be set in operation by applying power to rotate shaft 12 which, through its connections with shaft 11, causes the latter to oscillate through ninety degrees and the platen 19 is, therefore, oscillated through this same amplitude. As the platen moves from the position shown in Fig. 1 to that shown in Fig. 2, the outwardly curling ends of the strips of color stock engage the approaching color card blank 35 and are pressed down against the cutter plates so as to be held in position on the color card blank during the final period of clockwise motion of the platen 19 which presses the intermediate portions 69 of the cutter plates into a substantially continuous surface in a common plane, thereby causing the cutting edges 71 to sever the projecting ends of the color strips across the cutting edges 72 and 72'. It will be observed 40 that the chips are severed from the strip stock and affixed to the color card blank to complete the card during this instant of engagement and pressure contact. It will be evident that this operation may be carried on with great rapidity. Where higher speeds are desired, cam or other 45 mechanism adapted to provide the requisite dwells in the motion of the platen, may be substituted for that shown.

As the platen moves in a counter-clockwise direction an attendant may remove the finished 55 color card and place another color card blank in position on the platen. As the platen returns to the position shown in Fig. 1 with a new blank in position, the projection 21 engages the projection 22 and opens the valve 23 to cause the proper amount of solvent to be discharged from the spray nozzle 26, and the operations just described are repeated. It will be evident that, if desired, the nozzle 26 may be directed toward the adhesive bearing ends of the color strips instead of 60 at the blank as shown. Moreover, thermoplastic adhesive may be used and rendered effective by heating elements carried by the platen or by the plate 56, or an open flame may be applied directly to the color card blank or to the ends of 65 the strips of color stock. Therefore, the term "activating agent" as used in the claims is intended to cover the application of heat where thermoplastic adhesive is used, as well as the application of a solvent for other adhesives. In 70 75

any case, the adhesive may be carried either by the color strips or by the color card blank.

While the features of the invention and the manner and process of making, constructing and using it, and the best known mode of applying the principles thereof have been illustrated and described herein, it will be understood that various modifications will occur to those skilled in the art when informed by this specification, and that the invention is not limited except as indicated by the appended claims.

What is claimed is:

1. The combination of members movable relatively toward and from each other for effecting pressure contact between color strips and a color card blank disposed between said members, means effective substantially as said members come into pressure transmitting relationship for severing said color strips to form color chips for attachment to said color card blank, and yieldable means for supporting said strips while they are being severed, said pressure transmitting relationship being effective as the strips are severed to hold the severed portions against said color card blank.

2. The combination of relatively movable members for effecting pressure contact between a color card blank and portions of color strips disposed between said members, means for exposing between said relatively movable members the portions of said color strips to be affixed to said color card blank, means for activating a layer of adhesive covering the exposed portion of the color strips, and means for severing said exposed portions from said color strips.

3. Apparatus of the class described comprising guide means for conducting color strips, means having cooperating cutting edges adjacent said guide means, means tending to hold said cutting edges spaced to receive each color strip to be severed, and means for simultaneously pressing a color card blank against the portions of said color strips extending beyond said cutting edges and for severing said portions.

4. Apparatus of the class described comprising means having cooperating cutting edges, means tending to hold said cutting edges spaced to receive color strips to be severed, and means for simultaneously pressing against a color card blank those portions of the color strips extending beyond said cutting edges and for pressing said cutting edges together to sever said portions of said color strips.

5. Apparatus of the class described comprising guide means for conducting superposed color strips, a plurality of plates having cooperating cutting edges disposed across said guide means, means tending to hold the cutting edges of adjacent plates spaced to receive a color strip from the guide means, and means for simultaneously pressing against a color card blank those portions of the color strips extending beyond the cutting edges and for causing said cutting edges to sever said extending portions of said color strips.

6. Apparatus of the class described comprising guide channels for conducting superposed color strips, a plurality of plates having cooperating cutting edges extending across said guide channels and spaced longitudinally therealong, means tending to hold the cutting edges of adjacent plates spaced to receive a color strip from a guide channel, and means for simultaneously pressing against a color card blank those portions of the color strips extending beyond the cutting edges

and causing said cutting edges to sever said extending portions of said color strips.

7. Apparatus of the class described comprising means having cooperating cutting edges, means tending to hold said cutting edges spaced to receive color strips to be severed, yieldable means for supporting the color strips beneath said cutting edges, and means for pressing a color card blank against those portions of the color strips extending beyond said cutting edges to sever said extending portions of said color strips.

8. Apparatus of the class described comprising guide channels for conducting superposed color strips, a plurality of plates having cooperating cutting edges extending across said guide channels and spaced longitudinally therealong, means tending to hold the cutting edges of adjacent plates spaced to receive a color strip from a guide channel, elastic tubes extending across said guide channels adjacent said cutting edges for supporting color strips, and means for simultaneously pressing against a color card blank those portions of the color strips extending beyond the cutting edges and causing said cutting edges to sever said extending portions of said color strips.

9. Apparatus of the class described comprising a plurality of plates having cooperating cutting edges for severing a color strip disposed therebetween, one of said plates supporting the portion of the color strip extending beyond said cutting edges for pressure contact with a color card blank, whereby said extending portion of said color strip may be held in pressure contact with a color card blank as said extending portion is severed by said cutting edges.

10. Apparatus of the class described comprising adjacent plates angularly disposed to a common plane, each plate having cutting edges, a cutting edge of one plate being adapted to cooperate with a cutting edge of an adjacent plate, said angularly disposed plates being depressible substantially into a common plane for causing the cooperating cutting edges to sever color strips disposed therebetween and for causing said plates to support the portions being severed from the color strips for pressure contact with a color card blank.

11. Apparatus of the class described comprising adjacent plates angularly disposed to a common plane, each plate having cutting edges, a cutting edge of one plate being adapted to cooperate with a cutting edge of an adjacent plate, said angularly disposed plates being depressible into said common plane for causing the cooperating cutting edges to sever color strips disposed therebetween and for causing said plates to support the portions being severed from the color strips for pressure contact with a color card blank.

12. Apparatus of the class described comprising plates angularly disposed to a common plane, each plate having cutting edges, a cutting edge of one plate being adapted to cooperate with a cutting edge of an adjacent plate, guide means for conducting color strips to said cooperating cutting edges, said angularly disposed plates being depressible substantially into a common plane for causing the cooperating cutting edges to sever color strips disposed therebetween and for causing said plates to support the portions being severed from the color strips for progressive pressure contact with a color card blank.

13. Apparatus of the class described comprising

- ing plates angularly disposed to a common plane each plate having cutting edges, a cutting edge of one plate being adapted to cooperate with a cutting edge of an adjacent plate, yieldable means for supporting color strips adjacent said cooperating cutting edges, said angularly disposed plates being depressible substantially into a common plane for causing said cooperating cutting edges to sever color strips disposed therebetween and for causing said plates to provide support for the portions being severed from the color strips for progressive pressure contact with a color card blank.
14. Apparatus of the class described comprising plates angularly disposed to a common plane, each plate having cutting edges, a cutting edge of one plate being adapted to cooperate with a cutting edge of an adjacent plate, guide means for conducting color strips to said cooperating cutting edges, and elastic elements disposed along said cooperating cutting edges for yieldably supporting color strips, said angularly disposed plates being movable substantially into a common plane for causing said cooperating cutting edges to sever color strips disposed therebetween and for causing said plates to provide support for the portions being severed from the color strips for progressive pressure contact with a color card blank.
15. The method of severing a color chip from a strip and affixing the chip to a color card blank which comprises yieldably supporting the portion

to be severed from the strip at an angle to the surface of the color card blank while progressively effecting pressure contact between said blank and said portion so as to cause substantially the entire surface of said portion to come in contact progressively with said color card blank, and then severing said portion from the strip.

16. The method of severing a color chip from a strip and affixing the chip to a color card blank which comprises providing a layer of adhesive between the color card blank and the portion to be severed from the color strip, yieldably supporting said portion of the strip at an angle to the color card blank, activating said adhesive, progressively effecting pressure contact between said blank and said portion so as to cause substantially the entire surface of said portion to come in contact progressively with said color card blank, and then severing said portion from the strip.

17. In a device of the class described, a member adapted to support color strips, a member adapted to support a blank, said members being movable into pressure transmitting relationship, and means operable to sever color chips from the color strips as said members are brought into pressure transmitting relationship, said means serving to hold severed chips against the blank and thereby attaching the severed chips to the blank to form a color card.

SAMUEL H. SMITH.
